GUN BARREL MOUNTING

Samuel G. Green, Gray, Ga.

Application November 20, 1936, Serial No. 111,867

5 Claims. (Cl. 89—14)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a gun barrel mounting.

In the water-cooled type of machine gun, the barrel is surrounded by a water-jacket and since it has a reciprocating movement relative thereto, it is necessary to provide packings for the movable joints to prevent leakage of the cooling medium.

10 This invention relates to the front mounting of a gun barrel and its purpose is to provide an arrangement whereby the packing member is confined between the barrel bearing member and a gland which are adjustable relative to the front end cap of the water-jacket so that the packing may be correctly positioned and which are adjustable relative to each other so that the packing may be maintained under the proper compression.

15 Another object of the invention is to provide compactly arranged locking members for holding the bearing and gland in adjusted position.

20 A further object is to so arrange the assembly that the movable bearing member may be applied and removed from the front end of the gun.

To these and other ends, the invention consists 25 in the construction, arrangement and combination of elements described hereinafter and pointed out in the claims forming a part of this specification.

30 A practical embodiment of the invention is illustrated in the accompanying drawing, wherein:

Fig. 1 is a longitudinal sectional view of the front portion of a machine gun showing the improved mounting.

35 Fig. 2 is a sectional view on the line 2—2 of Fig. 1.

Referring to the drawing by characters of reference there is shown the front portion of a machine gun comprising a barrel 5 which is disposed in a jacket 6 adapted to contain a cooling medium. A front end cap 7 on the jacket is formed with a fixed cylindrical sleeve 8 having a reduced internal diameter at its inner end to establish an inclined shoulder 9. A bearing member 10 inserted in and threaded to the sleeve has an offset 11 adapted to contact the shoulder 9 and provide an inner end 12 of reduced diameter for slidably supporting a movable sleeve 13. The sleeve 13 has a front turned end 14 threaded to the muzzle of the

gun barrel and serving to space the body of the sleeve from the barrel as shown in my prior Patent 2,026,528 of January 7, 1936, for the purpose of enabling the cooling medium to be in direct contact with the front end of the barrel. 5

A gland 15 disposed within and threaded to the bearing member 10 serves as a support or bearing for the front part of the sleeve 13 and also confines a ring 16 which embraces the sleeve 13 and holds a packing member 17 against the forward and inner wall of the offset 11 of the bearing member 10. The gland extends beyond the front end of the bearing member and is provided with teeth 18 whereby it may be engaged by a tool and rotated. The gland acts through 15 the ring 16 to place the packing member under proper compression.

The bearing member 10 is provided with an aperture 19 for receiving the inner end of a hollow set screw 20 which is disposed radially of the end cap 7 and is threaded in a thickened portion thereof. A pin 21 within the hollow set screw 20 is held against the gland 15 by means of a set screw 22 which is also within the hollow set screw 20 and threaded thereto. A nut 23 is threaded on the outer end of the inner set screw 22 and jammed against the outer face of the hollow set screw 20. The set screws maintain the bearing member 10 and gland 15 against movement relative to one another and also relative to the end cap. As a result of this arrangement, the packing member 17 will always be maintained in the proper position and under the proper compression, and the adjustment need not be changed during the life of the gun barrel. 30 35

A ring 24 threaded on the inner end of the fixed sleeve 8 is formed with a flared apron 25 to facilitate introduction of the barrel unit.

I claim.

1. In a machine gun, a jacket for a cooling 40 fluid and having a front end cap, a gun barrel mounted for reciprocation within the jacket, a fixed sleeve on the cap and having an internal shoulder, a bearing member for the barrel threaded in the fixed sleeve and having an off- 45 set engaging the internal shoulder of the sleeve, said bearing member having an aperture, a gland threaded in the bearing member and adapted to support the gun barrel, a packing confined between the gland and the offset of the 50 bearing member, a hollow set screw in the end cap and inserted in the aperture of the bearing member, a pin in the hollow set screw, and a set screw in the hollow set screw and holding the 55 pin against the gland.

2. In a machine gun, a jacket for a cooling fluid and having a front end cap, a gun barrel mounted for reciprocation within the jacket, a fixed sleeve on the cap, a bearing member for the barrel threaded in the fixed sleeve, said bearing member having an aperture, a gland threaded in the bearing member and adapted to support the gun barrel, a packing confined between the gland and the bearing member, a hollow set screw in the end cap and inserted in the aperture of the bearing member, a pin in the hollow set screw, and a set screw in the hollow set screw and holding the pin against the gland.
3. In a machine gun, a jacket for a cooling fluid and having a front end cap, a gun barrel mounted for reciprocation within the jacket, a fixed sleeve on the cap and having an internal shoulder, a bearing member for the barrel threaded in the fixed sleeve and having an offset engaging the internal shoulder of the sleeve, a gland threaded in the bearing member and adapted to support the gun barrel, a packing confined between the gland and the bearing member, and means carried by the end cap and
5. In a mounting for a reciprocable gun barrel, a fixed sleeve, a bearing member threaded in the sleeve and having a barrel-supporting portion, a barrel supporting gland within the bearing member and threaded thereto, a packing confined between the gland and bearing member, a hollow set screw in the sleeve and locking the 10 bearing member, and means in the hollow set screw for locking the gland.
4. In a mounting for a reciprocable gun barrel, a fixed sleeve, a bearing member threaded in the sleeve and having a barrel-supporting 15 portion, a barrel supporting gland within the bearing member and threaded thereto, a packing confined between the gland and bearing member, and means carried by the sleeve and engaging the bearing member and gland to lock 20 them against movement relative to one another and relative to the sleeve.

SAMUEL G. GREEN.
